His Attorney.

UNITED STATES PATENT OFFICE.

WILLIS ALDEN ISHLER, OF PITTSFIELD, MASSACHUSETTS, ASSIGNOR TO GENERAL ELECTRIC COMPANY, A CORPORATION OF NEW YORK.

ELECTRICAL INSULATION.

1,223,881.

Specification of Letters Patent. Patented Apr. 24, 1917.

Application filed September 11, 1916. Serial No. 119,449.

To all whom it may concern:

Be it known that I, WILLIS ALDEN ISHLER, a citizen of the United States, residing at Pittsfield, county of Berkshire, State 5 of Massachusetts, have invented certain new and useful Improvements in Electrical Insulation, of which the following is a specification.

My invention relates to insulating barriers or pads such as are used for insulating electrical windings. An object of my invention is to provide insulating barriers or pads which are particularly capable of withstanding effects of high frequency and which are 15 of general application to various types of apparatus.

It has been discovered that films or layers of insulating oils, at least of such oils as are now commonly used for submerging electrical apparatus, are particularly capable of maintaining high insulating characteristics under the high frequencies to which some electrical apparatus, particularly transformers, are occasionally subjected. Other 25 common insulating materials and structures are liable to unexpected failures under the application of high frequencies. By my invention I secure in insulating barriers or pads the advantages of this property of oil, 30 as well as its better known insulating properties, by employing totally inclosed impervious casings containing oil as in the form of films or layers, preferably in the form of sheets of oil soaked fibrous material.

At one or both sides of the oil layer may be applied one or more thicknesses of other insulating materials as conditions may dictate, for example to render the whole barrier more or less fire proof. A structure of 35 this kind may be made in the form of a fairly flexible pad which may be wrapped around the part to be insulated thereby. Such a structure is self contained and is 40 protected against modification by outside influences. The oil thereof cannot be displaced nor absorb moisture or other foreign fluids and thereby the pad lose its expected strength. The pad may therefore be applied before the apparatus of which it is a 45 part is subjected to the impregnating or varnishing treatments which are commonly applied to assembled apparatus, for the fluid materials of these treatments have no access to the oil chamber.

55 The structure of my invention is of gen-

eral application, that is, is applicable both to devices submerged in oil and to those not submerged in oil, such as, for example, air blast transformers; in both cases the enveloping casing retains the oil of the insulating 60 structure in its original quantity and purity. It is even possible therefore by employing my invention to obtain some of the advantages of oil insulation in apparatus not submerged in oil.

65 In the accompanying drawing and the following detailed description I have illustrated and described the best embodiment of my invention that I am now aware of, and such as I have found after a long course of 70 tests, to possess very desirable characteristics. Figure 1 is an elevation of an insulating barrier or pad embodying my invention such as is suitable for use between the primary and secondary windings of small 75 transformers. Figs. 2 and 3 are sections thereof respectively on the lines 2-2 and 3-3 of Fig. 1. Fig. 4 is a perspective of the pad of Fig. 1 in substantially the form it assumes in the transformer of Fig. 5. Fig. 80 5 is a plan view of a transformer provided with pads such as are illustrated in the preceding figures.

The pad of the drawing is made up of a 85 number of layers of different insulating materials. The center layer 10 comprises a sheet of blotting paper thoroughly soaked or saturated with insulating oil, for example such oil as is now used for submerging 90 transformers. At each side of this sheet 90 of oil soaked blotting paper is a sheet 11 of pasted mica (that is, scraps of mica film pasted together into the form of a sheet and thoroughly compressed) between thicknesses of paper. Totally inclosing these sheets of 95 insulating materials is a wrapping 12 of varnished cambric which is impervious to most fluids.

In applying the impervious wrapping of 100 varnished cambric to produce the pad illustrated in the drawing, the oil soaked blotting paper and the mica and paper sheets are assembled upon substantially the center of a sheet of varnished cambric cut to the requisite size. One edge, for example the 105 near edge of the varnished cambric, is then folded over the top mica sheet to the position indicated by the dotted line 15 of Fig. 1. The opposite or far edge of the cambric is likewise folded, but in the opposite direc- 110

tion, over the top mica sheet to the position 16 of Fig. 1. Where the edges 15 and 16 over-lap they are thoroughly stuck together by any suitable binder. Figs. 1 and 3 5 illustrate the overlapping of these edges of the cambric. The side edges of the cambric are then folded over and thoroughly stuck together, for example in the manner illustrated in Fig. 2. The overlapping edges 10 may be shellacked to form tight joints. This manner of folding the varnished cambric produces a totally inclosed impervious case or wrapping.

As this pad is applied to the transformer 15 of Fig. 5, it assumes a shape something like that illustrated in perspective in Fig. 4. In Fig. 5 two such pads are shown in position in a transformer. The windings of this transformer surround the middle leg 20 of the core 20. The windings comprise two low potential windings 21 and 22 and a high potential winding of two coils 23 and 24 between the two low potential windings. Ventilating spaces 25 are left between the 25 low potential winding 21 and the high potential winding, and likewise an annular ventilating space 26 is left between the two coils 23 and 24 of the high potential winding. After the low potential winding 22 is 30 applied to the core a barrier or pad 30, such as has been described hereinbefore, is wrapped around the same and over this is placed the high potential winding. On the outside of the high potential winding is 35 likewise placed a similar barrier or pad 31 and the low potential winding 21 is placed outside this barrier. Such a transformer may safely be impregnated with insulating materials after assembly as is now a common practice, for the totally inclosing impervious wrapping thoroughly excludes the impregnating material from the absorbent sheet of the pad and retains the oil thereof. Short circuits even close to the pad, 40 cannot entirely destroy the insulating properties of the pad due to the fire resisting qualities of the mica sheets. As will be ap-

parent, the insulation between the primary and secondary windings being entirely self contained and protected against contamination by the impervious wrapping is especially adapted to retain its insulating properties even in the presence of decreased insulating properties in the other insulation of the device. Furthermore, 55 whether the transformer of Fig. 5 is submerged in oil or not during operation, some of the advantages of oil insulation are secured between the primary and secondary windings.

While I have described the principle of my invention and the best mode I have contemplated for applying this principle, other modifications will occur to those skilled in this art and I aim in the appended claims 65 to cover all modifications which do not involve a departure from the spirit and scope of my invention.

What I claim as new and desire to secure by Letters Patent of the United States, is,— 70

1. An insulating barrier comprising a relatively thin totally inclosed casing of an insulating material impervious to oil and a film of oil contained therein.

2. An insulating barrier comprising a relatively thin impervious totally inclosed casing and oil therein. 75

3. An insulating barrier comprising an oil soaked absorbent sheet and an impervious wrapping totally inclosing the same. 80

4. An insulating barrier comprising an oil soaked absorbent sheet, a sheet of fire resistant material at each side thereof and an impervious wrapping totally inclosing the same. 85

5. An insulating barrier comprising an oil soaked absorbent sheet, a sheet of insulating material at one side thereof and an impervious wrapping totally inclosing the same. 90

In witness whereof, I have hereunto set my hand this 24th day of Aug. 1916.

WILLIS ALDEN ISHLER.
